JAMES T. PAGE, OF ROCHESTER, NEW YORK.

Letters Patent No. 106,280, dated August 9, 1870.

BROILER.

The Schedule referred to in these Letters Patent and making part of the same.

To all whom it may concern:

Be it known that I, JAMES T. PAGE, of the city of Rochester, in the county of Monroe and State of New York, have invented a new and useful Improvement in the Construction of Meat-Broilers and Bread-Toasters, of which the following is a specification.

My improvements consist in the construction of the rim and the handle from a slight strip of sheet metal, with the ends forming the handle bent together, and secured as shown.

Also, in the construction of the rim, with the slots or incisions in its upper or lower edge, for the reception of the wire which forms the bottom; and

Furthermore, in combination therewith the grooved rim or drip-pan, substantially as hereinafter described.

In the drawing—

Figure 1 is a top view of my device, and

Figure 2, a side view of the same, slightly elevated from the drip-pan, which is shown in cross-section beneath.

A indicates the rim, made from a single strip of sheet metal, with the ends of the said strip lapped together and secured by rivets *g g*, to form the handle *b*.

In the top or bottom edge of the rim A, I provide slots or incisions, *d d*, of about equal distance apart, and preferably of the form shown in fig. 2.

These slots receive the wire strands *c c*, that are woven across from side to side of the rim, to form the wire grating D, on which the food rests.

I prefer to provide a drip-pan, B, having an annular groove *h*, and an opening, *k*, through the center, the pan B resting around the griddle-hole on top the stove, so as to allow the rim A to rest therein.

By this means the grease or drippings that flows

from the meat down the sides of the rim are caught in the groove *h* and prevented from besmirching the stove.

By constructing the rim A and handle *b* of a single strip of sheet metal, as described, the articles can be made much more cheaply and durable, and without the use of solder, which is liable to melt and allow the seams to part.

If desired, a handle of wood or other suitable material may be provided by securing it to the handle *b*.

Ordinarily, the wire bottom is made by weaving the wires across and drawing them through holes or perforations in the sides of the rim; but this process is laborious and expensive.

By means of the slots or incisions *d*, as in my device, the wire is inserted laterally into the edge of the rim, and the process of weaving the bottom is done much more rapidly and with less labor.

The slots *d* may be provided in the rims of gridirons that are made of either sheet or cast metal.

What I claim as my improvement, is—

1. The construction of the rim A and handle *b* of a single piece of sheet metal, in combination with the wire grating D, substantially as and for the purpose herein set forth.

2. In combination with the above, the drip-pan B, provided with the annular groove *h* and central opening *k*, substantially as and for the purpose described.

In testimony whereof I hereunto sign my name in the presence of two subscribing witnesses.

JAMES T. PAGE.
